UNITED STATES PATENT OFFICE

EDWIN GEORGE ANSON, OF BIRMINGHAM, ENGLAND, ASSIGNOR OF ONE-HALF TO
FRANK CLARKE, OF BIRMINGHAM, ENGLAND

AIR PISTOL

Application filed May 18, 1931, Serial No. 538,057, and in Great Britain July 9, 1930.

This invention relates to improvements in connection with air pistols, and it has for its primary object the provision of an improved means of cocking the pistol.

- 5 According to the present invention the air pistol is characterized by a side cocking lever fulcrumed on the end of the air cylinder and operatively connected to the spring plunger. The side cocking lever is fulcrumed 10 on the forward end of the air cylinder, slidably linked to the spring plunger, and normally secured at the breech end of the pistol by means of a snap-action catch arranged in association with a breech block 15 having an air tight closure action. A further feature is that the body part of the side cocking lever extends along the entire length of the air cylinder and is of an arcuate cross-section conforming closely to the exterior 20 curvature of the cylinder. A still further feature is that the breech block may be carried by the side cocking lever so as to be adapted for an inclined engagement with the breech end of the pistol and for wedging 25 engagement with a bridge provided on said breech end.

In order that the invention may be clearly understood and readily carried into practice, reference may be had to the appended 30 explanatory drawings, in which:—

Figure 1 is a side elevation of an air pistol in accordance with the invention, the side cocking lever being shown in its closed normal position.

Figure 2 is an opposite side elevation of the pistol, the view being partly in section so as to show the plunger in its cocked position.

Figure 3 is a plan view of Figure 1. 40 Figure 4 is a plan view of Figure 1 taken in section on the line 4—4, the plunger being shown in its uncocked position.

Figure 5 is a corresponding sectional plan view showing the spring plunger depressed 45 into its cocked position by an outward pivotal displacement of the side cocking lever, which is shown partly broken away.

Figure 6 is an end elevation of the nozzle of the pistol, the handle or stock being partly 50 broken away.

Figure 7 is a corresponding view of the breech end of the pistol.

Figure 8 is a cross-sectional view taken on the line 8—8 of Figures 1 and 4.

In a convenient embodiment of the invention, as applied by way of example to an air pistol having an air cylinder, an axial discharging barrel, and a spring plunger which operates in a direction towards the handle or stock when discharging, a side cocking lever 1 has its forward end disposed at right angles in the form of a centrally slotted lug or plate 2 so as to extend across the end of the pistol with the central aperture of the lug or plate in register with the outlet nozzle of the barrel 3, and this terminal lug or plate 2 of the cocking lever is fulcrumed in normally vertical hinge or pivot bearings 4 provided on the left-hand side of the discharge end of the pistol. The body part of this side cocking lever 1 extends along the entire length of the right-hand side of the air cylinder 5 and is of an arcuate cross-section conforming closely to the peripheral curvature of the cylinder, as may be seen particularly 75 in Figure 8, and is formed with an external reinforcing longitudinal rib 6. At a point 7 adjacent its fulcrumed end the side cocking lever 1 has pivotally attached thereto a link 8 which at its opposite end is slidably engageable with the spring-actuated plunger 9 by means of a small slide block 10 extending through a longitudinal side slot 11 in the cylinder 5. At its breech end the side cocking 80 lever 1 carries a breech block 12 of a width substantially equal to the diameter of the breech end of the air cylinder 5, this breech block 12 having a curved or tapering engagement with the breech end 13, and having a 85 tapered or wedge shaped terminal nose 14 which passes under and engages with a bridge 15 provided on the breech end 13. The inner face of the breech block 12 is formed with an air duct in the form of a recess 16 which constitutes a by-pass between the outlet air duct 17 from the air cylinder 5 and the axial discharging barrel 3 of the pistol, as may be seen particularly in Figure 4, and this by-pass duct 16 is surrounded by a flexible 100

jointing washer 18 which insures an air-tight closure when the breech block 12 is pressed against the breech end 13 by wedging contact with the bridge 15. The breech block 12 has a snap-action catch attachment 19 which engages over the bridge 15 so as to retain the breech block in position when the piston is fired, this catch 19 having a pressure spring 20 and being preferably formed with a terminal fingerpiece 21 which facilitates release of the catch for recocking the pistol after firing.

It will be seen that the right-hand side cocking lever 1, having the forward left-hand fulcrum mounting 4, is adapted to be swung outwardly and forwardly from its closed normal position shown in Figures 1 to 4 into the open position shown in Figure 5, this movement providing a particularly convenient and efficient means of cocking the pistol by forcing the spring plunger 9 from the inner position shown in Figure 4 into the outer position shown in Figures 2 and 5, in which cocked position the plunger is held by the sear catch 22 of the trigger 23 as shown in Figure 2. It will further be seen that the side cocking lever 1 is adapted to be retained in the firing position in a particularly secure and effective manner by means of the wedge and catch mechanism associated with the bridge 15.

In a modification, the breech block may be hinged to the left-hand side of the breech end instead of being carried by the side cocking lever, the snap-action catch in this case being appropriately mounted for the purpose of ensuring the necessary air-tight closure and locking action.

40 I claim:—

1. An air pistol which comprises, in combination, a stock, an air cylinder, a laterally inclined breech end on the cylinder, a discharging barrel located axially within the cylinder, a spring-actuated plunger operating within the cylinder in a direction towards the stock when discharging, a trigger having a sear catch engageable with the plunger, a side cocking lever fulcrumed on the forward end of the cylinder, a link pivoted to the side cocking lever and slidably connected to the plunger, a laterally inclined breech block carried by the side cocking lever so as to have an air-tight closure engagement with the inclined breech end, a bridge projecting from the breech end, a terminal nose on the breech block having a wedging engagement with the bridge, the air cylinder having an outlet air duct through the breech end thereof, the breech block having a by-pass air duct to connect the air cylinder with the discharging barrel, and a snap-action catch which normally secures the side cocking lever at the breech end of the pistol.

65 2. An air pistol comprising an air cylin-

der, a barrel within said air cylinder, a slideable plunger within the air cylinder and around the barrel, a spring tending constantly to move said plunger rearwardly through the air cylinder, a cocking lever pivoted to the air cylinder and operatively connected with the plunger for moving the latter forwardly through the air cylinder to a cocked position, trigger releasable means to hold said plunger in its cocked position, the barrel opening through the rear end of the air cylinder the cocking lever lying normally against the side of the air cylinder, a breech block carried by the cocking lever to overlie the rear ends of the air cylinder and the barrel when the cocking lever is in its normal position, and means providing communication through said breech block between the rear end of the air cylinder and the rear end of the barrel when the breech block is disposed in overlying relation to the rear ends of said cylinder and barrel whereby, upon release of the plunger, air is forced from the cylinder through the barrel.

3. An air pistol as set forth in claim 2 in which the cocking lever is mounted on a vertical pivot for lateral swinging movement relative to the air cylinder.

4. An air pistol as set forth in claim 2 in which the cocking lever extends across the forward ends of the air cylinder and the barrel and is pivoted at its forward end to the forward end in front of the air cylinder, the said forward end portion of said lever having an opening for alignment with the barrel when the lever is in its normal position.

5. An air pistol as set forth in claim 2 in which a bridge member is carried by the rear end of the air cylinder and in which a formation is provided on the breech block for engagement with said bridge member to force the breech block tightly against the rear end of the air cylinder when the cocking lever is swung to its normal position.

6. An air pistol as set forth in claim 2 in which a latch is carried by the breech block for cooperation with the air cylinder to releasably hold the cocking lever in its normal position and the breech block in overlying relation to the rear ends of the air cylinder and the barrel.

7. An air pistol as set forth in claim 2 in which a bridge member is carried by the rear end of the air cylinder, in which the front face of the breech block and the rear end of the air cylinder are inclined to the axis of the cylinder for wedging engagement, and in which a formation is provided on the breech block for engagement by said formation to hold the breech block against rearward movement thereby to cause the breech block to become wedged tightly against the rear end of the air cylinder when said block is swung to a position to overlie the end of the cylinder.

8. An air pistol as set forth in claim 2 in which the air cylinder is provided with a slot to accommodate the connection between the cocking lever and the plunger, and in
5 which the cocking lever in its normal position lies snugly against the barrel in covering relationship to said slot.

10 In witness whereof I have hereunto set my hand.
EDWIN GEORGE ANSON.
